UNITED STATES PATENT OFFICE.

ALAN R. FERGUSSON, OF BUFFALO, NEW YORK.

TOY DANGER SIGNAL.

Application filed November 7, 1922. Serial No. 599,605.

To all whom it may concern:

Be it known that I, ALAN R. FERGUSSON, a citizen of the United States, residing at Buffalo, in the county of Erie and State of New York, have invented certain new and useful Improvements in Toy Danger Signals, of which the following is a specification.

This invention relates to toy or miniature signal devices especially adapted to be used in connection with toy railways, and particularly to a miniature danger signal device, an object of the invention being to provide an improved device of this class, which will be rigid, strong and durable in use, and which will be relatively economical and inexpensive to manufacture.

A further object of this invention is to provide an improved toy danger signal having a supporting stand formed from a single length of metal such as wire, thereby providing a toy device, which will not only be rigid and strong for the purpose desired, but will be cheaper in construction due to the reduction in the number of steps in the manufacture and the amount and character of the material used.

Other objects of this invention will appear in the following description thereof, reference being had to the accompanying drawings forming a part of this specification wherein like reference characters indicate corresponding parts in the several views and wherein Fig. 1 is a perspective view illustrating an embodiment of my invention; and Fig. 2 is a fragmentary rear view of the upper part of the device.

The present improved toy signal device comprises in general a supporting stand including a supporting base having an upright member extending therefrom, and a stationary signal element herein shown as a danger signal element supported in fixed position by said upright member. In its preferred form the danger signal device of my invention is preferably formed from a single length of wire and as illustrated in this instance comprises a wire base 9, formed by bending or coiling one end of a wire of suitable length. The wire is bent inwardly at 10 toward the center of the coil 9 and then is bent upwardly to form the supporting upright member 11 of suitable height. A stationary signal or warning member 12 comprising a skeleton formed rectangular member shown as a diamond shaped member

having a suitable warning printed thereon is secured to the upright wire 11. This diamond shaped member is shown provided with a pair of cross bars, one a horizontal bar and the other a vertical bar crossing each other centrally of the diamond shaped member, the vertical bar running in parallelism with the wire upright. It will of course be understood that this signal element may be connected to the upright 11 in various ways, but in the present instance I have preferably connected the member 12 to the wire 11 by means of clamping projections or tongues 13, formed integrally from the vertical cross bar 14 of the danger sign. The projections or tongues 13 are bent around the wire post 11 and are located one at each side of the horizontal cross bar and firmly embrace the same so as to hold the sign element rigidly in position, and also cause the vertical bar to conform to the shape of the wire upright.

From the foregoing it will be seen that I have provided an improved toy danger signal device which may be manufactured at a minimum of expense and yet at the same time will be strong and serviceable in use. The entire supporting stand is preferably constructed of wire, and as shown may be quickly formed by bending a single length of wire into the desired shape. With the coiled base 9 a stand is provided which will set firmly upon the floor and to which may be quickly connected a suitable stationary sign element, such as the member 12 and the latter may be stamped out of sheet metal having integral means for connecting the same to the supporting stand, thus providing a device of minimum cost.

It will be understood that by describing in detail herein any particular form, structure, or arrangement, it is not intended to limit the invention beyond the terms of the several claims or the requirements of the prior art.

I claim as my invention:

1. A toy railway warning device comprising a wire formed supporting base having an upright wire, and a diamond shaped warning member secured to said upright wire.
2. A toy railway warning device comprising a wire formed supporting base having an upright wire, and a skeleton formed rectangular warning member secured to said upright wire.

3. A toy railway warning device comprising a wire formed supporting base having an upright wire, and a warning member secured to said upright wire and comprising a skeleton formed rectangular member having one or more cross bars.
4. A toy railway warning device comprising a wire formed supporting base having an upright wire, and a warning member secured to said upright wire and comprising a skeleton formed rectangular member having a pair of cross bars, one having a clamping clip encircling the upright wire.
5. A toy railway warning device comprising a wire formed supporting base having an upright wire, and a warning member secured to said upright wire and comprising a diamond shaped member, having horizontal and vertical bars crossing each other, the vertical bar having a clamping clip encircling the upright wire.
6. A toy railway warning device comprising a wire formed supporting base having

an upright wire and a warning member secured to said upright wire and comprising a diamond shaped member having horizontal and vertical bars crossing each other, the vertical bar having a pair of clamping clips one at each side of the horizontal bar for clamping the warning member to the upright wire.

7. A toy railway warning device comprising a wire formed base having one end extending radially inward and upward to provide a single upright wire and a stamped out warning member secured to said upright wire and comprising a diamond shaped member having a pair of cross members crossing each other centrally of the diamond shaped member and one thereof having stamped metal clips for securing the diamond shaped member to the upright wire.

Signed at Buffalo, N. Y., this 2nd day of November 1922.

ALAN R. FERGUSSON.
